CLAIM

The ornamental design for a bracelet, as shown and described.

DESCRIPTION

FIG. 1 is a perspective view of a first embodiment of a bracelet showing our new design;

FIG. 2 is a front elevational view thereof;

FIG. 3 is a perspective view of a second embodiment of the bracelet; and,

FIG. 4 is a front elevational view of FIG. 3.

The broken lines shown in FIGS. 1-4 represent unclaimed portions of the bracelet and form no part of the claimed design.

1 Claim, 4 Drawing Sheets
